US0D1089874S

(12) **United States Design Patent** (10) **Patent No.:** **US D1,089,874 S**
Salyer (45) **Date of Patent:** **** Aug. 19, 2025**

(54) **3 TIERED SLOW FEEDER KITTY TREAT TOWER**

(71) Applicant: **Danielle Salyer**, Denver, CO (US)

(72) Inventor: **Danielle Salyer**, Denver, CO (US)

(**) Term: **15 Years**

(21) Appl. No.: **29/918,244**

(22) Filed: **Nov. 27, 2023**

(51) **LOC (15) Cl.** **30-03**

(52) **U.S. Cl.**

Primary Examiner — Susan Moon Lee

CLAIM

The ornamental design for a 3 tiered slow feeder kitty treat tower as shown and described.

DESCRIPTION

FIG. 1 is a perspective view of a 3 tiered slow feeder kitty treat tower in accordance with the present design;

FIG. 2 is a front view thereof;

FIG. 3 is a rear view thereof;

FIG. 4 is a right view thereof;

FIG. 5 is a left view thereof;

FIG. 6 is a top down view thereof; and,

FIG. 7 is an underside view thereof.
